CLAIM

The ornamental design for an interlocking paving block, as shown and described.

DESCRIPTION

FIG. 1 is a top perspective view of the interlocking paving block of the present invention.

FIG. 2 is a top plan view of the interlocking paving block of FIG. 1.

FIG. 3 is a bottom plan view of the interlocking paving block of FIG. 2.

FIG. 4 is a front and elevation view of the interlocking paving block of FIG. 2 taken in the direction of line 4—4, the opposite end being a mirror image thereof; and,

FIG. 5 is a right side end elevation view of the interlocking paving block of FIG. 2 taken in the direction of line 5—5, the opposite end being a mirror image thereof.

1 Claim, 2 Drawing Sheets

FIG. 1**FIG. 2**

FIG. 3**FIG. 4****FIG. 5**

UNITED STATES PATENT AND TRADEMARK OFFICE
CERTIFICATE OF CORRECTION

PATENT NO. : Des. 429,530
DATED : August 15, 2000
INVENTOR(S) : Andy F. Fleishman

Page 1 of 1

It is certified that error appears in the above-identified patent and that said Letters Patent is hereby corrected as shown below:

In the DESCRIPTION:

Line 7, correct "front and elevation" to read --front end elevation--.
Line 9, correct "thereof; and" to read --thereof.--

Signed and Sealed this
Tenth Day of July, 2001
